UNITED STATES PATENT OFFICE.

CHARLES L. MCCUEN, OF EVANSTON, ILLINOIS, ASSIGNOR, BY MESNE ASSIGNMENTS,
TO DELCO-LIGHT COMPANY, OF DAYTON, OHIO, A CORPORATION OF DELAWARE.

ROTARY PRESSURE OR VACUUM PUMP.

Application filed November 1, 1919. Serial No. 335,033.

To all whom it may concern:

Be it known that I, CHARLES L. MCCUEN, a citizen of the United States, residing at Evanston, in the county of Cook and State 5 of Illinois, have invented certain new and useful Improvements in Rotary Pressure or Vacuum Pumps, of which the following is a specification.

The invention relates to rotary pressure 10 or vacuum pumps, and the object of the invention is to provide a rotary pressure or vacuum pump in which the friction will be reduced to the minimum and the maximum efficiency obtained from the pump for a 15 given expenditure of power.

It is a further object of the invention to provide in a rotary pressure or vacuum pump employing an intermeshing pair of gears mounted to rotate upon anti-friction 20 bearings an improved construction to prevent internal leakage in the pump.

A further object of the invention is to improve the general construction of the various component parts of the pump casing 25 containing the inlet and outlet headers for both the fluid refrigerant and the pump sealing and lubricating fluid, thereby securing certain described advantages and economies in manufacture, installation, operation, and in making any necessary repairs 30 to the pump subsequent to installation.

Other objects of the invention will appear from the preferred embodiment of the invention as set forth in the following specification, which is also depicted in the accompanying drawings.

In carrying out the invention a pair of gears are employed, which mesh with each other and rotate in opposite directions, the 40 gears being housed in a casing with an admission port at one side and an exhaust port at the other. The gear casing is preferably submerged in a liquid having access through restricted passages to the discharge side of 45 the gears, but being excluded from the inlet side. The gears fit with a working fit within the casing and the liquid acts as a seal to prevent any leakage past the gears and prevents the passage of any gas from 50 the inlet to the discharge, other than that which is carried in the space between the teeth of the gears.

In the said drawings, Fig. 1 is a side elevation view of the pump with a portion of 55 the discharge or exhaust pipe broken away

and with the admission duct and valve mechanism controlling same in section.

Fig. 2 is a sectional view on line 2—2 of Fig. 1 looking in the direction indicated by the arrows. 60

Fig. 3 is a longitudinal sectional view on broken line 3—3, taken in the direction indicated by the arrows.

Figs. 4 to 8 inclusive are perspective views 65 showing details of some of the component parts serving as end closures, bearing supports and portions of the inlet and outlet headers of the casing.

In the preferred form of the invention embodied in the pump herein shown and described, the pump mechanism is contained in a casing of special design adapted to be attached to the wall of a closed chamber, the body or barrel of the pump enclosing the operating gears being adapted to be located within the chamber, there being a head casting *a* provided with a peripheral flanged portion 10 adapted to be secured on the exterior of the chamber wall surrounding an opening therein that will be formed to permit the passage of the body portion of the pump therethrough, the pump barrel or casing proper protruding on the interior of the chamber, not herein shown, as the same forms no part of the invention, for the 85 pump may obviously be attached to its support in any other desired manner. The flanged portion 10 of the head casting *a* is provided with a plurality of spaced openings 11 through which its securing bolts are 90 passed, and the body portion of the head casting *a* will be preferably formed as illustrated as a substantial continuation of the design in cross section of the parts making up the pump barrel or casing proper 95 enclosing the pump gears, so that when the pump is installed by being bolted to its enclosing chamber wall, the opening in the chamber wall will be closed by the body of head casting *a*, and the opening sealed 100 by reason of the peripheral flanged portion 10 and suitable packing as desired, as well understood in the art, and not herein shown.

The head casting *a* is provided with a boss 12 (Figs. 1 and 3) adapted to protrude 105 on the exterior of the pump when installed, there being an opening through the entire casting including the boss 12, through which the main drive shaft *b* of the pump is passed longitudinally, and in which a suitable bear- 110

ing therefor is provided by contracting the opening on the side of the casting adjacent the interior of the pump barrel as indicated at 13, the said opening being enlarged outwardly to the extreme outer end of the boss 12, where it is screw threaded, as indicated at 14, for the reception of a combined bearing member and packing gland closure plug screw threaded, and adapted to co-operate therewith, the same being indicated by reference character 15, and having preferably at its outer extremity a portion angular in cross section as indicated at 16 for the reception of a tool to be used in adjusting the same in relation to the head casting, it being adapted to be secured in its adjusted position by lock nut 17.

In a pump of the described character, it is very desirable that this bearing for the operating shaft be constructed to prevent leakage of fluids from the interior of the pump and hence the desirability of elongating the packing gland and bearing as herein provided, the space between the contracted portion 13 of the bearing and the bearing and gland closure plug 15 surrounding the shaft being preferably filled with a suitable packing material as a coil of fibrous cord or rope indicated by reference character 18, wound circumferentially of the shaft so that whatever pressure thereon desired may be secured by the adjustment of the closure plug bearing 16. As a further means of securing a fluid tight joint around the drive shaft *b* within the gland, I find it advantageous to insert with the packing one or more rings of some soft ductile material, lead being preferred, as indicated by reference character 19, the same being adapted to closely surround the drive shaft *b* and also to contact with the wall of the gland housing. At right angles to the axis of the bearing for the shaft *b* in the head casting *a* and in the boss 12 thereon there is a duct or passage 20, the same extending through the body of the boss 12 adapted to serve as an inlet passageway for the fluid refrigerant which the pump is particularly adapted to circulate, as sulphur dioxide (SO_2), and extending at right angles to the passage 20 and parallel with the drive shaft through the body of the head casting *a* and boss 12 thereon is the communicating passageway 21 through which fluid refrigerant will be passed to the interior of the pump or casing, being introduced into the passage 20 as common in refrigerating machines, from a pipe forming a part of the circulatory system of the machine and communicating with the valved fitting therein as indicated by reference character 22 shown particularly in vertical section in Fig. 1, the inlet passage 23 thereof being provided with the contracted portion or seat 24 adapted to be closed by suitable means as the ball valve 25 normally held against said seat 24 by coil spring 26 so that the valve will open to permit ingress of refrigerating fluid or other fluid adapted to enter the intake port of the pump, thus preventing any return flow from the pump through the circulatory system supplying same, but opening to supply fluid to the pump. The valve fitting 22 is screw threaded into the boss 12 closing one end of the passageway 20 on the exterior of the boss while the other extremity of the passage 20 is closed by a suitable plug or stop cock as indicated at 27, which may be formed as a pipe fitting and adapted to serve as a connection for the attachment of means for charging the system, in which my pump will be connected in series as described, with an initial supply or renewal supply of fluid refrigerant.

The working parts of the pump are comprised chiefly in a pair of intermeshing gears, each of which is preferably for convenience in manufacture, of a composite character, one of the gears being secured to rotate with drive shaft *b* and consisting of composite parts 28 and 29, while a second composite gear shown as made up of the parts 30, 31 rigidly secured to a shaft *e* extending beyond the extremity of the gear portion to form journal or trunnion portions for engagement with its bearing supports. The intermeshing gears 28, 29 and 30, 31 preferably have their teeth arranged in what may be termed herring-bone or double spiral formation as illustrated for example in U. S. Patent 1,233,069 granted July 10, 1917 to G. I. Leonard, and being adapted to rotate when normally operating in the directions indicated by the arrows in Fig. 2, so that as the pockets formed in the gears between their teeth move out of intermeshing relation with the opposing gear teeth the fluid in the inlet 32 communicating with intake passage 21 for the refrigerant is sucked into the gas pockets between the teeth and thence carried therein up and around the gears as the latter revolve to be later acted upon by the gear teeth which intermesh with these pockets or spaces between the teeth on the reverse side of the gears, this intermeshing action being a progressive one, so that as the gears continue to rotate, the fluid, coming through intake passage 21 and inlet 32 formed as a groove on the inner surface of main gear enclosing casing *f* and extending longitudinally of the casing and communicating throughout the length of the gears, is forced from the inner ends of the pockets or spaces between the teeth of the gears toward the ends thereof at the ends or outer extremities of the gears adjacent the end walls of the gear casing, the fluid in this operation passing first downwardly through passageways 33 and 34 to the common duct or discharge passage 125

35 in casing *f*, which communicates with the pump discharge pipe 36, which may be extended to any convenient point of discharge for the fluid being compressed or pumped. 5 Passageway 33 is formed merely as a recess on the inner pump chamber side of an end plate *c* while the passageway 34 is a similar recess in end plate *d* but communicating with an orifice 37 which registers with the 10 common discharge passage 35 in casing *f* and with an orifice 38 in bearing plate *g*, the last mentioned orifice registering with an opening 39 in end plate *h* and with the 15 duct 40 in discharge pipe 36. *j* is a bearing plate similar to plate *g* interposed between the end plate *c* and the head casting *a*, and both the plates *g* and *j* are preferably provided with enlarged openings surrounding 20 gear shafts *b* and *e* designated by the reference characters 41 and 42 in the former and by reference characters 43 and 44 in the latter, designed to receive and retain in position suitable anti-friction bearing devices as indicated generally by reference characters 25 45 to 48 inclusive, as shown in section in Fig. 3.

The construction described affords an admirable means for supporting and retaining the ball bearings in correct position and 30 the fact that the composite pump casing is made up of the various integral parts, as described, makes these bearings easily accessible when the pump is disconnected. Each of the component parts of the pump casing 35 comprising plates *j*, *c*, main gear casing *f*, plates *d*, *g*, and *h* are provided with registering openings, four in number, designated as follows:

In plate *j* by reference characters 49 to 40 52 inclusive, in plate *c* by reference characters 53 to 56 inclusive, in plate *d* by reference characters 57 to 60 inclusive, in plate *g* by reference characters 61 to 64 inclusive and in end plate *h* by reference characters 45 65 to 68 inclusive, these plates being assembled in the order named and as indicated in Figs. 1 and 3 in a unitary assembly, which may be independent of the head casting *a*, by the four elongated securing bolts 69 to 50 72 inclusive, each of which is provided with suitable securing nuts, and locking devices, if desired, as illustrated. The elongated bolts 69 to 72 inclusive may be provided with heads protruding on the outside surface of bearing plate *j*, which heads are adapted to be accommodated in the assembly by counter sunk portions or recesses as indicated at 73, Fig. 1, so that the assembled pump casing may then be attached to the 55 head casting *a* by suitable retaining bolts, the heads or nuts of which are shown only in Fig. 1, and indicated by reference characters 74, 75, there being preferably four or more of such securing bolts used, the same 60 being passed through the openings 76 to 79

inclusive, and registering with similar openings in head casting *a*.

80 is a baffle plate which may be secured around the discharge pipe 36 near its union with the pump casing the union being preferably secured by means of a suitable connecting casting as indicated at *k*, which may be secured in position with the orifice 81 therein, registering with the discharge passage from the pump casing of which the 75 opening 39 in the outer end plate *h* forms a part, as described.

The purpose of the baffle plate 80 is to prevent an upward current or circulation of any fluid or gaseous refrigerant that 80 might become mixed with the liquid in which the pump is normally immersed when in operation.

The operation of the device has been alluded to in the description of the details of construction and it will be understood that the rotation of the gears in the direction indicated by the arrows in Fig. 2 and by reason of the fact that these gears are designed to be sealed by means of some suitable liquid, as lubricating oil, to be admitted through the vertical ducts or pipes 82 to 86 inclusive, there being eight of such liquid pipes on the type of pump herein illustrated, five of which are shown by reason of the character of drawings in side elevation and section, Figs. 1 and 2, will cause these gear teeth to separate or withdraw on the upper side thereof as illustrated in the drawings, causing a vacuum and exerting a 90 pull upon fluid refrigerant past the ball valve 25 into the duct 32, which will be carried around the periphery of the gears to the lower sides thereof to be discharged, 100 by reason of the herring-bone construction of the gears, progressively in an outward direction and into the passageways 33 and 34 and through the outlet duct 40 from the pump. The liquid intake tubes 86 protrude 110 downwardly from the casing and there are detachable tubes provided with specially constructed contracted discharge orifices as indicated by reference character 87, Fig. 2, the tubes being detachable by threading the ends of same adjacent the said orifices and inserting same in correspondingly threaded openings in main gear casing *f* having the ducts as indicated at 88 communicating with the interior of the casing and within the housing for the gears, so that the pull or 115 suction that will be maintained around the described portions of the peripheries of the gears will, when the pump is operating, tend to draw the sealing liquid in which the pump will preferably be immersed.

Heretofore in fluid gear pumps of the character to which my invention is applied, it has been the common practice to expose the inlet side of the intermeshing gears to a practically free and unrestricted immer-

sion or circulation of the sealing bath or liquid as the lubricating oil or its equivalent commonly employed, with the result as I have discovered, pumps so constructed lose 5 a great amount of efficiency due to the fact that a larger amount of the sealing fluid than is normally necessary to properly film and perform its desired sealing function will be entrapped between the gears and such 10 surplus must be compressed or forced therefrom with consequent loss of power. With my improved construction, in which the gears are excluded from the bath of sealing fluid except as supplied through the graduated 15 and readily selected ducts 87 in the feed tubes, no more of the sealing fluid may be admitted than will properly function.

It is found in practice that the amount of sealing liquid to properly supply the pump 20 can be determined by graduating the openings 87 in the oil feed tubes for a given condition of oil or other liquid and for given temperature conditions, hence the reason for making these tubes detachable and permitting 25 the interchange of tubes with the desired feed orifices therein as may be required to accommodate any particular condition.

Obviously, the discharge of fluid entering 30 through intake passage 32 will have commingled therewith in the discharge passage 35 and the passage 40 leading from the pump a quantity of sealing fluid as the oil, together with the refrigerant or other fluid 35 being pumped, the refrigerant being usually a fluid in the form of a gas and will pass after discharge into the space above the oil or other liquid refrigerant in which the pump is immersed.

40 91 indicates threaded lock rings on threaded gear shafts *b* and *e*. 94 indicates a series of registering aligning holes adapted to take dowel pins in connecting the various parts of the pump casing together.

45 The outer end of drive shaft *b* is shown provided with one part of a partially flexible coupling including plate 92 secured to the shaft by set screw 93 and a plurality of pins 94, 95 engaging suitable means on the 50 power supplying shaft not shown.

While I have shown and described the preferred embodiment of my invention, it will be apparent that persons skilled in the art may vary the details without departing 55 from the purpose and spirit of the invention, and what I claim as new and desire to secure by Letters Patent is:

1. A fluid pump comprising in combination, a gear casing and closely fitting intermeshing gears rotatably mounted therein, there being an inlet passageway on one side of the intermeshing portions of said gears, and a discharge passage leading from adjacent the said intermeshing portions of the 60 gears and from the casing, and means ac-

tuated by the pump for feeding by suction action a suitable sealing liquid to the gears comprising a member of tube-like formation detachably secured adjacent an opening passing through the walls of said casing. 70

2. A fluid pump comprising in combination a gear casing and closely fitting intermeshing gears rotatably mounted therein, there being an inlet passageway on one side of the intermeshing portions of said gears and a discharge passage leading from adjacent the said intermeshing portions of the gears and from the casing, and means actuated by the pump for feeding by suction action a restricted volume of a suitable sealing liquid to the gears comprising a detachable member of tube-like formation having an opening extending longitudinally thereof, there being a restricted passageway forming a continuation of the normal opening in the said tubular member. 75

3. A fluid pump comprising in combination a gear casing and closely fitting intermeshing gears rotatably mounted therein for pumping the refrigerant, said gear casing being provided on the interior thereof with two substantially cylindrical chambers, the axes of which are arranged in parallelism and the peripheries of the circumferential portions of said chambers intersecting, whereby the said gears may intermesh, there being an inlet passageway formed in the inner wall of said gear casing adjacent the intersecting portions of said gear chambers, the said passageway extending approximately parallel with the axes of said gear chambers, closure plates adapted for attachment with the ends of the gear casing adjacent the said chambers therein, means for detachably securing said end closure plates to the gear casing, means for feeding fluid to be pumped through the closure at one end to the said inlet passageway, means for conducting fluid from adjacent the gears through the end closure plates and the said casing to the exterior of said pump, said gear casing being provided with an aperture and means whereby a sealing fluid may be introduced through said aperture into said casing by the suction of said pump only. 105

4. A fluid pump comprising in combination, a gear casing and closely fitting intermeshing gears rotatably mounted therein, said gear casing being provided on the interior thereof with two substantially cylindrical chambers the axes of which are arranged in parallelism and the peripheries of the circumferential portions of said chambers intersecting whereby the said gears may intermesh, there being an inlet passageway formed in the inner wall of the said gear casing adjacent the intersecting portions of said gear chambers, the said passageway extending approximately parallel with the axes of said gear chambers, closure 110 120 125 130

- plates adapted for attachment with the ends of the gear casing adjacent the said chambers therein, means for detachably securing said end closure plates to the gear casing, 5 means for feeding fluid to be pumped through the closure at one end to the said inlet passageway, means for conducting fluid from adjacent the gears through the end closure plates and the said casing to the exterior 10 of said pump, said gear casing being provided with an aperture, and means whereby a sealing fluid may be introduced through said aperture into said casing by the suction of said pump only and means for rotatably 15 supporting said gears.
5. A fluid pump comprising in combination a gear casing and closely fitting intermeshing gears rotatably mounted therein, said gear casing being provided on the interior thereof with two substantially cylindrical chambers, the axes of which are arranged in parallelism and the peripheries of the circumferential portions of said chambers intersecting whereby the said gears may 20 intermesh, there being an inlet passageway formed in the inner wall and at the top of said gear casing adjacent the intersecting portions of said gear chambers, the said passageway extending approximately parallel with the axes of said gear chambers, 25 closure plates adapted for attachment with the ends of the gear casing adjacent the said chambers therein, means for detachably securing said end closure plates to the gear casing, means for feeding fluid to be pumped through the closure at one end to the said inlet passageway, and means for permitting the passage of a restricted volume of a suitable sealing liquid through the walls of the 30 gear chambers therein at the lower portion thereof.
6. A fluid pump comprising in combination a gear casing and closely fitting intermeshing gears rotatably mounted therein, 35 means for rotating said gears comprising in part a drive shaft operatively connected with one of said gears and extending on the exterior of the gear casing, said gears having teeth on the peripheries thereof disposed obliquely or in herring-bone relation with the vertex of their angle at their first point of contact, there being an inlet passageway formed on the interior of the casing on one side of the intermeshing portions 40 of said gears and in communication with said intermeshing portions of said gears from end to end of said gears and discharge passages formed in the end walls of the gear casing, there being one of said discharge passages at each end of the gears adjacent their contiguous or intermeshing portions and on the side of their point of engagement opposite to that of the inlet passageway, there being a duct connecting 45 said discharge passages, and means for venting
- ing said last mentioned duct on the exterior of the pump casing.
7. A fluid pump comprising in combination a gear casing and closely fitting intermeshing gears rotatably mounted therein, 70 said gear casing being formed with the extremities thereof open for admission of said intermeshing gears, end closure plates for said gear casing, there being an inlet passage formed in certain of said end closure plates and communicating with a groove formed on the interior wall of the gear casing, there being outlet passages formed also in certain of said end closure plates, said outlet passages opening into a common discharge passage formed in the casing wall but out of communication except through said passageways with the interior of the pump casing, and means for venting the 75 said common discharge passageway on the exterior of the pump casing.
8. A fluid pump comprising in combination, a gear casing and closely fitting intermeshing gears rotatably mounted therein, 80 there being inlet and outlet passageways in communication with said gears for fluid to be pumped, the inlet passageway being formed as an extension on the inner wall of the casing and communicating with the interior thereof adjacent the point of contact of said intermeshing gears at one side thereof, detachable plates for closing the ends of said gear casing, there being exhaust ports formed in the walls of certain of said end closure plates and opening at the opposite side of the gears from the said inlet passageway, said exhaust ports opening into a common passageway formed in the casing 85 wall and out of contact except through said exhaust ports with the interiors of the pump casing, and means for permitting the entry of a restricted volume of suitable sealing liquid to the gears on the interior of the pump casing.
9. A fluid pump comprising in combination, a gear casing and closely fitting intermeshing gears rotatably mounted therein, end closure plates adapted to close the open ends of the gear casing, said plates being provided with openings therein adapted to permit the passage therethrough of suitable shafts for rotatably supporting the said intermeshing gears, bearing plates adapted to be secured to the ends of said casing on the respective exterior surfaces of said end closure plates, there being enlarged openings in said bearing plates around the shafts for supporting said gears, anti-friction bearings in said enlarged openings in the bearing plates, and means for securing said bearing plates, said end closure plates and said gear casing together to form a substantially rigid pump casing.
10. A fluid pump comprising a casing and intermeshing gears rotatably mounted 130

therein, said casing having an inlet passage above the line of intermesh of the gears, and discharge passages located at the opposite ends of the gears and connected by a passage below the line of intermesh of the gears.

11. A fluid pump comprising a casing and intermeshing gears rotatably mounted therein, said casing having an inlet passage above the line of intermesh of the gears, and discharge passages located at the opposite ends of the gears and connected by a passage below the line of intermesh of the gears, and means for supplying a sealing liquid in restricted volume to the lower

sides of the gears at points prior to the discharge of the refrigerant therefrom.

12. A fluid pump comprising a casing, intermeshing gears rotatably mounted therein, end plates at the opposite ends of such casing, plates *g* and *j* adjacent the end plates, plates *d* and *c* interposed between the plates *g* and *j* and the casing, and means for detachably securing the plates and casing together to form a unitary structure.

In testimony whereof I have signed my name to this specification on this 24th day of October, A. D. 1919.

CHARLES L. McCUEN.
